UNITED STATES PATENT OFFICE.

KNOWLES YOUNGBLOOD, OF ATLANTA, GEORGIA.

PACKAGE.

Application filed March 12, 1926. Serial No. 94,260.

This invention relates to a package designed primarily for holding soft collars, one of the objects of the invention being to provide an envelope having open ends 5 for the reception of a holding strip on which a collar is designed to be mounted, this strip being so shaped as to frictionally engage the envelope and hold the strip against accidental displacement while the package 10 is being handled.

A further object is to provide a simple and inexpensive structure of this character which can be used for holding laundered collars and can also be used as original packages 15 in which the collars are sold.

With the foregoing and other objects in view which will appear as the description proceeds, the invention resides in the combination and arrangement of parts and in 20 the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a perspective view of the package, a collar and its holding strip being shown partly withdrawn from the envelope.

Figure 2 is a longitudinal section on line 35 2--2 Figure 1, the holding strip and the collar being shown in plan housed within the envelope.

Figure 3 is a section on line 3--3 Figure 2.

Referring to the figures by characters of reference 1 designates an elongated flat tube open at its ends and preferably formed of a transparent or semi-transparent paper although it can obviously be made of any other material desired. If this tube is 40 formed of a thin paper easily torn, one end thereof can be reinforced by a band 2 of tough paper affixed to and extending around said end. A holding strip of cardboard or the like, indicated at 3 is designed to be 45 inserted into the reinforced end of the tubu-

lar casing or envelope 1 and the advancing end of this strip is folded so as to provide a flap 4. The length of the strip 3 when folded as shown in Figure 1 is slightly greater than the length of the tubular envelope or casing 1 so that when the strip is properly seated within the casing, one end portion will project a short distance beyond the envelope as shown in Figure 2, thus affording a part which can be gripped readily 55 between the fingers when it is desired to withdraw the strip 3 from the envelope.

In using the device herein described a collar indicated at C is placed on the strip 3 with one end inserted between the strip and 60 the flap 4. That end of the strip carrying the flap is then inserted into the reinforced end of the tubular casing or envelope 1 and pressed longitudinally until the collar is 65 completely housed in said envelope and the parts located as shown in Figure 2. The natural resiliency of the strip 3 will result in the rounded free end 5 of the flap 4 bearing outwardly against one side of the tubular casing or envelope 1 with sufficient force 70 to prevent the strip 3 from slipping out of place within the envelope.

As before pointed out the package herein described can be used for holding collars that have been laundered or they can be used 75 as original packages at the factory.

What is claimed is:

A package including a tubular paper casing having open ends, a reinforcing member extending around and affixed to one 80 of the ends of the casing, and a holding strip insertable longitudinally into the casing through the reinforced open end thereof, said strip having its advancing end portion folded to provide a flap, there being a 85 space between the strip and its flap for the reception of one end of an article to be housed within the casing, the free end of the flap constituting means for frictionally engaging the casing to hold the strip against 90 displacement relative to the casing.

In testimony that I claim the foregoing as my own, I have hereto affixed my signature.
